UNITED STATES PATENT OFFICE.

PHILIP DIRECTOR, OF BROOKLYN, NEW YORK.

DESIGN FOR A BUTTON.

44,302.

Specification for Design.

Patented July 8, 1913.

Application filed April 15, 1913. Serial No. 761,353. Term of patent 3½ years.

To all whom it may concern:

Be it known that I, PHILIP DIRECTOR, a citizen of the United States, residing at Brooklyn, in the county of Kings and State of New York, have invented a new, original, and ornamental Design for Buttons, of which the following is a specification, reference being had to the accompanying drawing, forming a part thereof.

Referring to the drawings, Figure 1 is plan view of a button of my design; Fig. 2 is an elevation thereof; Fig. 3 is an elevation thereof from another view point.

I claim—

The ornamental design for a button as shown.

PHILIP DIRECTOR.

Witnesses:

NATHAN ROSOVSKY,

GEORGE L. THOM.
